UNITED STATES PATENT OFFICE.

DAVID FREEDLINE, OF BROOKLYN, NEW YORK.

HAT STRETCHER AND SHAPER.

1,426,285.

Specification of Letters Patent. Patented Aug. 15, 1922.

Application filed June 9, 1921. Serial No. 476,209.

To all whom it may concern:

Be it known that I, DAVID FREEDLINE, a citizen of the United States, and a resident of the city of New York, borough of Brooklyn, in the county of Kings and State of New York, have invented a new and Improved Hat Stretcher and Shaper, of which the following is a description.

My invention relates to hat shapers and stretchers for shaping a hat to conform it to the individual shape of the cranium.

The invention has for an important object to provide a device of the indicated character having increased possibilities in localized adjustments of the shaping and stretching elements to very effectively conform the hat to the peculiarities of conformation in a particular cranium.

The invention has also for an object to provide a practical embodiment of the invention reflecting practical considerations with respect to the convenience and speed of adjustment, as well as to promote facility of operation.

The nature of the invention, its distinctive features and characteristics, as well as other objects of the invention will clearly appear as the description proceeds.

Reference is to be had to the accompanying drawings forming a part of this specification, it being understood that the drawings are merely illustrative of one example of the invention.

Figure 1 is a plan view of my improved hat stretcher and shaper;

Figure 2 is an enlarged sectional side elevation of a portion of the same on the line 2—2, Figure 1;

Figure 3 is a detail in vertical section on the line 3—3 of Figure 1;

Figure 4 is an enlarged side elevation of a portion of the hat stretcher and shaper showing more particularly the latch pawl provided on each screw rod;

Figure 5 is a detail in horizontal section given to show the lateral movement of the screw rod with the angular adjustment of individual stretching and shaping elements as well as the space provided to afford clearance for said movement;

Figure 6 is a perspective view of one of the individual stretching and shaping elements.

In carrying out my invention in accordance with the illustrated example a suitable frame or body 10 is provided in which are

approximately radial slots 11 to afford clearance for the depending shanks 13 of the individual stretching and shaping elements 12. Said shanks 13 have transverse 60 threaded holes 14 therein with which screws 15 for operating the slide have threaded engagement, said screws having squared ends to receive a key or equivalent turning means. The elements 12 are disposed above 65 the top of the body 10 and the shanks 13 extend downwardly through holes 16 in slide plates 17 that rest on shoulders 11^a formed in the body 10 at the slots 11 as shown in Figure 3.

The screws 15 extend freely through tubular guide elements 18 which are disposed in the slots 11, the lower portion 11^a of each slot being widened or under-cut as best seen in Figure 5. The outer portion of the screw 75 is formed with parallel annular ratchet members 19 adapted to be engaged by a latch pawl 20 provided for each screw, said pawl being pivoted near one end as at 21, on the front flange 25 provided on the guide 80 element 18. The opposite end of the pawl 20 has a suitable handle 22 and a spring 23 bears against the under side of the pawl in a notch 20^a therein, said spring being secured to or engaged by a pin 24 on said 85 flange 25. On the flange 25 at the lower edge is an inwardly directed guide member 26 extending beneath the body 10. The tubular guide element 18 is made flat to rest on the body 10 at the bottom of the slot 11, the flat form and the member 26 preventing 90 turning movement of said element 18, in response to the turning of the screw 15.

With the described arrangement the turning of the screw 15 about its own axis by a 95 detachable crank handle (not shown) or other means, applied to the squared outer end thereof will cause the element 12 engaged thereby and the slide 17 associated with said element to have sliding movement 100 radially inward or outward to effect a stretching action on the hat. The latch 20 serves to hold the screw in a given approximate adjustment after a sliding axial movement of the screw and element 12. In addition to its axial movement the screw 15 may be swung through an arc in the widened or under-cut lower portion 11^a of the slot 11 from one side of said slot to the other as will be clear from Figure 1, the swinging movement being about the vertical axis of the element 12. The swinging of the screw 110

turns the shank 13 and the shaping element 12 correspondingly to thereby vary the angular position of element 12 to better conform the hat to the conformation of the 5 cranium at a local point.

In the present example of my invention I provide a coiled spring cable 27 as the means for holding the several guide elements 18 in position by preventing radial movement 10 thereof, said cable being secured to the body 10 at the rim thereof by eyes or keepers 28 on said body between adjacent guides 18.

The numeral 50 indicates a crescentic auxiliary shaping element adapted to be disposed outside of any three of the elements 12, the novelty of said auxiliary shaping element as illustrated, residing in locking lugs 51 at the interior of said auxiliary element and directed radially inward, said lugs being 20 positioned to be entered between adjacent elements 12.

I would state in conclusion that while the illustrated example constitutes a practical embodiment of my invention, I do not limit 25 myself strictly to the mechanical details herein illustrated, since manifestly the same can be considerably varied without departure from the spirit of the invention as defined in the appended claims.

Having thus described my invention, I 30 claim:

1. A hat stretcher and shaper including a series of individual stretching and shaping elements, and screws on which said elements 35 are mounted, said screws being adapted to have relative approximately radial movement and being angularly adjustable individually to vary the angular positions of said elements.

2. A hat stretcher and shaper including stretching and shaping elements mounted for individual sliding movement, and separate screws having threaded engagement with the individual elements, said screws being 45 movable axially to impart sliding movement to the elements and swingable laterally to cause said elements to have movement about a vertical axis.

3. A hat stretcher and shaper including 50 separate stretching elements, screws having threaded engagement with said elements, for causing travel of said elements on the screws by a turning of the latter, and guides through which said screws pass, said screws 55 being movable axially through said guides

to give traveling movement to said elements and said guides being movable laterally through an arcuate path to give laterally swinging movement to the screws for varying the angular positions of said elements. 60

4. A hat stretcher and shaper comprising a body having radial slots undercut at their lower portions, at each side of the medial planes of the respective slots, slides on said body at the slots, stretching and shaping elements disposed above the body and having shanks extending downwardly through said slots, screws having threaded engagement with the shanks of the stretching and shaping elements, and tubular guides into which 70 said screws may have turning and axial movement, said slides being movable laterally in the undercut portions of the slots to swing the screws laterally for varying the angular positions of said elements. 75

5. A hat stretcher and shaper comprising a body having radial slots undercut at their lower portions, at each side of the medial plane of the respective slots, slides on said body at the slots, stretching and shaping elements disposed above the body and having shanks extending downwardly through said slots, screws having threaded engagement with the shanks of the stretching and shaping elements, and tubular guides into which 80 said screws may have turning and axial movement, said guides being movable laterally in the undercut portions of the slots to swing the screws laterally for varying the angular positions of said elements; together 85 with pivoted spring-pressed latches on the guides, the screws having annular rigid members engageable by said latches. 90

6. A hat stretcher and shaper comprising a body, stretching and shaping elements 95 slideable on said body, screws for determining the positions of said elements, guides through which said screws extend, and a flexible cable extending about said body and outside of said guides to retain the latter in position. 100

7. In a hat stretcher and shaper, a series of individual stretching and shaping elements, and an auxiliary stretching and shaping element adapted to lie outside of a plurality of the first-mentioned elements and 105 having members thereon directed approximately radially inward to enter between the adjacent ends of the first-mentioned elements.

DAVID FREEDLINE.
